AUTOMATIC COFFEE MAKER

Carlton H. Johns, Downers Grove, and Kenneth R. McKee, Chicago, Ill., assignors to American Name Plate & Manufacturing Company, Chicago, Ill., a corporation of Illinois

Application May 26, 1950, Serial No. 10,218

Term of patent 14 years

(Cl. D44—26)

To all whom it may concern:

Be it known that we, Carlton H. Johns and Kenneth R. McKee, citizens of the United States, residing at Downers Grove, in the county of Du Page and State of Illinois, and at Chicago, in the county of Cook and State of Illinois, respectively, have invented a new, original, and ornamental Design for Automatic Coffee Maker, of which the following is a specification, reference being had to the accompanying drawing, forming a part hereof, wherein:

Fig. 1 is a front perspective view of an automatic coffee maker, showing our new design.

Fig. 2 is a top plan view.

The dominant features reside in the parts drawn in full lines as shown.

We claim:

The ornamental design for an automatic coffee maker, substantially as shown and described.

CARLTON H. JOHNS.

KENNETH R. MCKEE.
